FRED A. GRINOLDS AND EMIL E. MARTINSON, OF GLOBE, ARIZONA.

MUCK-SCOOPING APPARATUS.

1,371,785.

Specification of Letters Patent. Patented Mar. 15, 1921.

Application filed May 13, 1920. Serial No. 381,095.

To all whom it may concern:

Be it known that we, FRED A. GRINOLDS and EMIL E. MARTINSON, citizens of the United States, residing at Globe, in the 5 county of Gila and State of Arizona, have invented certain new and useful Improvements in Muck-Scooping Apparatus; and we do hereby declare the following to be a full, clear, and exact description of the 10 invention, such as will enable others skilled in the art to which it appertains to make and use the same.

This invention relates to muck scooping apparatus and it consists in the novel features hereinafter described and claimed.

An object of the invention is to provide apparatus of simple and durable structure adapted to be used in mines, stopes and drift shafts for scooping muck and depositing the same in a car or other receptacle preparatory to its removal from the mine or shaft.

With this object in view, the apparatus comprises an arch bar adapted to be placed 25 in the mine or shaft with its legs at the opposite sides of a track or roadway. A car is adapted to move along the track or roadway and may be of usual pattern. An I-beam is pivotally connected with the upper intermediate portion of the arch bar and a longitudinally extensible prop is mounted at the free end of the I-beam and is adapted to be engaged with the sides of the drift or shaft. A carriage is mounted 30 for movement along the I-beam and is provided with stop devices which may be engaged in notches provided in the beam, whereby the carriage may be stopped at suitable points along the beam. A block

40 is detachably mounted in the carriage and a releasing means is provided which may be manually manipulated for detaching the block from the carriage. A scoop is connected with the block. A cable is trained 45 over pulleys mounted upon the carriage and under a pulley mounted upon the block and is connected with the carriage. The said cable is trained around a pulley mounted upon the prop and the end portions of the 50 said cable are arranged to wind upon drums which are mounted upon a vertically disposed prop positioned in the shaft or drift at one side of the track or roadway and which carries a suitable engine adapted to 55 operate the drums to effect the winding or unwinding of the cable.

In the accompanying drawings:

Figure 1 is a side elevation view of the muck scooping apparatus.

Fig. 2 is an enlarged elevation of the carriage mounted on the I-beam and the block suspended from the carriage. 60

Fig. 3 is a vertical transverse section through the parts shown in Fig. 2 and illustrating the block in position within the 65 carriage.

Fig. 4 is a front elevation of the carriage showing the lock releasing cam member.

Fig. 5 is a detail elevation showing the 70 transversely disposed longitudinally extensible prop at the forward end of the beam.

Fig. 6 is a detail elevation of the upper portion of the arch bar.

As illustrated in the accompanying drawings, a track 1 is positioned upon the floor of the shaft or drift and a car 2 is arranged to move along the track in a usual manner. The scooping apparatus comprises an arch bar 3 provided at its ends with adjustable 80 spikes 4 adapted to be engaged with the floor of a shaft or drift at the opposite sides of the track 1 whereby the intermediate portion of the arch bar 3 is disposed over the track and bridges the same. An I-beam 5 85 is pivotally connected at one end with the upper intermediate portion of the arch bar 3 and carries at its free end a transversely disposed longitudinally extensible prop 6, the ends of which may be engaged with the 90 side walls of the shaft or drift. A pulley 7 is mounted upon the intermediate portion of the prop 6. The lower flange of the I-beam 5 is provided at intervals along its length with notches 8. An arm 9 is connected with the lower flange of the I-beam 5 in the vicinity of the arch bar 3 and carries at its lower end a pivoted hook 10, the 95 purpose of which will later appear.

A carriage 11 is mounted for movement 100 along the I-beam 5 and is provided with journaled wheels 12 adapted to travel upon the upper surfaces of the lower flanges of the I-beam, the said wheels being journaled upon the carriage at the inner surfaces of 105 the sides thereof. A pulley 13 is journaled upon the carriage 11 at a point below the I-beam. The prop 14, of usual structure is adapted to be positioned in an upright posture in the mine or drift at one side of the 110 track 3 and an engine 15 is mounted upon the prop 14. Drums 16 and 17 are jour-

naled upon the prop 14 and are operatively connected with the engine 15 whereby the said drums may be rotated by the engine when the same is in operation. A cable 18 is arranged with its opposite ends connected with the drums 16 and 17 and this cable is adapted to be wound upon first one of these drums and then the other during operation of the apparatus, as will be later clearly understood. The cable 18 is trained over pulleys 19 mounted upon the intermediate portion of the arch bar 3 and one run of the cable 18 is trained over the pulley 13 mounted upon the carriage 11 and passes through the carriage 11 and is secured to the same at the point 20. From the point 21 on the carriage 11, the cable is extended and trained over the pulley 7 and is then extended back over one of the pulleys 19 and led to the drum 17.

A block 21 is adapted to be received in the carriage 11 between the sides thereof and the said block is provided with a journaled pulley 22 under which the cable 18 passes. The block 21 is provided at its sides with vertically disposed cleats 23 which are approximately wedge-shaped in side elevation. Stop members 24 are pivotally mounted upon the sides of the carriage 11 and are held toward the same by means of springs 25. The free end portions of the blocks 24 pass through openings 26 provided in the sides of the carriage and under the influence of the springs 25 the inner portions of the blocks may enter the notches 8 upon the I-beam 5 whereby the carriage may be stopped in its movement upon the I-beam and when the stops engage in the notches. When the block 21 is in position between the side walls of the carriage 11, the outer surfaces of the cleats 23 engage the inner surfaces of the stops and force them outwardly against the tension of the springs 25, whereby the inner portions of the stops are held beyond the outer edges of the lower flanges of the I-beam 5.

Levers 30 are fulcrumed at the sides of the carriage 11 and are provided at their inner sides with blocks 31 which pass through the sides of the carriage 11 and which are adapted to extend under the lower ends of the cleats 23 when the block 21 is in position in the carriage 11. Springs 32 are connected with the free end portions of the levers 30 and with a cam 34 and are under tension with a tendency to hold the blocks 31 under the lower ends of the cleats 23. The cam 34 is pivoted upon the carriage 11 and its cam surface is in engagement with the free ends 60 of the levers 30. The cam member 34 is provided with an arm 35 to which a cable 36 is attached and the said cable 36 carries a handle grip 37. A bail 38 is pivotally connected with the lower portion of the block 21 and a scoop 39 is carried by the

bail 38. The scoop 39 is provided at its rear end with an eye 41 with which may be engaged the hook 10 carried by the arm 9, (previously mentioned).

The operation of the muck scooping apparatus is as follows:—The car 1 is moved to a point on the track between the arch bar 3 and the pile of muck which is to be removed from the stope or shaft. The engine 15 is then operated so that the cable 18 is 75 unwound from the drum 16 and wound upon the drum 17, therefore the carriage 11 is moved along the I-beam 5 until the carriage and the scoop are above the pile of muck. The operator then pulls upon the cable 36 80 whereby the cam member 34 is turned and the free ends of the levers 30 are swung outwardly from the sides of the carriage 11 and the blocks 31 are removed from under the lower ends of the cleats 23, thus the 85 block 21 and the scoop 39 may descend under the influence of gravity when the cable 18 is unwound from drum 16 and as the cleats 23 are withdrawn from between the stop members 24 the springs attached to the stop members draw the same into engagement with the notches 8 in the lower flange of the I-beam. Thus the carriage is temporarily held at a fixed position upon the I-beam. When the scoop 39 has been lowered in contact with the pile of muck, an operator uses the handles 40 and projects the scoop under the muck. The engine 15 is then operatively connected with the drum 16 whereby the cable 18 is wound upon the drum 16. 90 This will lift the block 21 and the loaded scoop 39 and when the lower ends of the cleats 23 pass above the upper edges of the levers 30, the said levers are swung under the lower ends of the cleats whereby the 95 block 21 is supported in the carriage 11. At the same time, the outer surfaces of the cleats 23 come in contact with the inner surfaces of the stop members 24 and force the 100 said stop members out of the notches 8 with 105 which they have been engaged. Therefore, the carriage is released upon the I-beam 5 and as the cable 18 continues to be wound upon the drum 16 and unwound from the drum 17 the carriage 11 is moved toward 110 the arch bar 3 and when the scoop 39 arrives in the vicinity of the arm 9, the hook 10 is engaged in the opening 41 and at the same time the operator pulls upon the cable 36 which disconnects the block from the 115 carriage as hereinbefore described, and the cable 18 unwound from the drum 16, thereby permitting the forward portion of the scoop to swing downwardly whereby the 120 contents of the scoop may gravitate from the same and fall into the car 2. This operation may be repeated until the car is 125 loaded when it may be removed from the shaft or drift along the roadway or track 1 in the usual manner.

Having described the invention what is claimed is:—

1. A scooping apparatus comprising an arch bar, a beam mounted upon the arch bar and having outwardly disposed flanges, a longitudinally extensible prop connected with the beam, a carriage mounted for movement along the beam, a block detachably connected with the carriage, means for releasing the block from the carriage, a scoop connected with the block, means for moving the carriage along the beam and for raising and lowering the block and means for detachably connecting the scoop with the beam.

2. A scooping apparatus comprising an arch bar, an I-beam pivotally connected with the arch bar, a longitudinally extensible prop connected with the I-beam, the I-beam being provided at intervals along its flanges with notches, a carriage mounted for movement along the flanges of the I-beam, spring controlled stops mounted upon the carriage and adapted to engage in the notches, a block detachably connected with the carriage and having cleats engageable with the stops to hold them out of the notches, means for releasing the block from the carriage, a scoop attached to the block, a cable connected with the carriage to move the same along the beam and connected with the block to raise and lower the same, and means mounted upon the beam and adapted to engage the scoop to swing the same as the delivery end of the scoop is lowered.

3. In a scooping apparatus, a beam, a carriage mounted for movement along the beam, means for securing the carriage to the beam, a block detachably mounted upon the carriage, said block having cleats, spring actuated levers fulcrumed upon the carriage and engageable under the cleats, and a cam member pivoted upon the carriage and having its cam edge in engagement with the levers.

4. A scooping apparatus comprising a beam, a carriage mounted for movement along the beam, a block detachably mounted upon the carriage and having cleats, spring actuated levers pivoted upon the carriage and engageable under the cleats, a

cam member pivoted upon the carriage and having its cam edge in engagement with the levers, and means for turning the cam member.

55

5. In a scooping apparatus, a beam, a carriage mounted for movement along the beam, means for securing the carriage to the beam, a block detachably connected with the carriage and having cleats, spring actuated levers pivoted upon the carriage and engageable under the cleats of the block, means for moving the levers from under the cleats, a scoop connected with the block and an arm mounted upon the beam, and means for connecting the arm with the scoop.

60

6. In a scooping apparatus, a beam, means positioned beneath one end of said beam for supporting the same, said supporting means being constructed to straddle a track beneath the beam, a carriage mounted for movement along the beam, a block detachably mounted upon the carriage and having cleats, spring actuated levers pivoted upon the carriage and adapted to engage the cleats, a cam member carried by the carriage to release the levers, and means for controlling the cam member.

65

7. A scooping apparatus comprising an arch bar, a beam mounted by one end on said arch bar, a carriage movable longitudinally of said beam, means for automatically locking said carriage in various positions upon said beam throughout the length thereof, a block detachably mounted upon the carriage and adapted to be held within the same at times, means for releasing said block, a scoop connected with said block, means carried by said beam for engagement with said scoop at times, a main operating cable connected with said carriage and with said block, guiding means for said main operating cable mounted on said beam, and controlling means for said main operating cable.
